his Attorney.

UNITED STATES PATENT OFFICE.

ANDREW W. GREEN, OF PEORIA, ILLINOIS.

TUNING-HAMMER.

SPECIFICATION forming part of Letters Patent No. 318,981, dated June 2, 1885.

Application filed October 3, 1883. (No model.)

To all whom it may concern:

Be it known that I, ANDREW W. GREEN, of Peoria, in the county of Peoria, in the State of Illinois, have invented an Improved 5 Tuning-Hammer; and I do hereby declare that the following is a full, clear, and exact description thereof, reference being had to the annexed drawings, making a part of this specification, in which like letters of reference refer to like parts, and in which—

Figure 1 represents a longitudinal section through the center; Fig. 2, a transverse section through *xx*; Fig. 3, an end view of the wrench B; Fig. 4, a view of the wrench combined with another form of handle.

The object of this invention is the construction of a tuning-hammer that shall be adapted to fit any size of pin upon which the wires are stretched in pianos, and one that shall be 20 capable of being used singly or doubly.

In the drawings, B B' represent the wrenches of the tuning-hammer; A, the socket-piece, and F the handle.

Tuning-hammers as usually made consist 25 of double wrenches B B', having square orifices in the ends, made to fit in each case one size of pin. To render these orifices O capable of fitting any size of pin within reasonable limits, I make them large enough to accommodate the largest pin to be met with in ordinary work, and secure at one side of each orifice a thin strip of steel, C, having means for fastening it at any point between the said side and the opposite one. Means for thus 30 adjusting said strip of steel C are found in the screws D and E. The two screws E press the end C' of this strip against the screws D, and these latter screws hold said strip firmly against the pin, the turning of which is to tune the 35 string connected therewith. The outer end of this strip C is bent into a foot, C', which, by being in the dovetailed notch O', prevents the same from dropping out from its containing orifice O. Said foot C' not only serves to 40 keep the strip C from getting out of place, but also becomes a guard to keep a pin from going behind the strip C if the pin were small and the strip therefore pressed farther away from the side of orifice O.

45 If, as often happens, it is not convenient to use in a certain part of the piano the double

tuning-hammer—such as is shown in Fig. 1—the wrench B can be removed from the other wrench and the handle, and the latter may be used alone. To make it thus removable, I 55 adapt its end B² to fit into the opening A' in the socket-piece A. The handle F, screwing into said socket-piece A, and pressing against the side of the inserted end B², prevents the same from being withdrawn therefrom and also 60 from being turned therein when under the pressure of being used in tuning.

By having three or four such indentations B² in the side of the end B² it becomes possible to dispense with the other wrench portion, 65 B', whose gripping-strip C is set at right angles to that of the other.

By putting the wrench B in a simple gimlet-handle, G, and fastening it therein by means of a set-screw, G', I am able to use it for turning the pins down into place previous to the tuning tension of the wire being reached.

What I claim as my invention, and for which I desire Letters Patent, is as follows, to wit:

1. In a tuning-hammer, the wrench B, having opening O, in combination with strip C and the screws D and E, substantially as and for the purpose specified.

2. In a tuning-hammer, the wrench B, having opening O and dovetail notch O', in combination with the strip C, having foot C', and the screws D and E, substantially as and for the purpose set forth.

3. The socket A, having wrench B' formed 85 as a part thereof, in combination with the wrench B, removable from said socket, and the handle F, having screw-threaded end, substantially as and for the purpose specified.

4. In a tuning-hammer, the socket A, having the wrench B', formed as a part thereof, in combination with the wrench B, detachable from said socket A and provided with means for retaining it therein, for the purpose set forth.

In testimony that I claim the foregoing invention I have hereunto set my hand this 28th day of September, 1883.

ANDREW W. GREEN.
